207,301

BATHROOM UNIT

Henry Blevio, 632 Warburton Ave., Apt. 7K,
Yonkers, N.Y. 10701

Filed Feb. 9, 1966, Ser. No. 977

Term of patent 14 years

(Cl. D4—4)

FIG. 1 is a perspective view of a bathroom unit showing my design;

FIG. 2 is a sectional view taken on the line 2—2 of FIG. 1; and

FIG. 3 is a sectional view taken on the line 3—3 of FIG. 1.

The sides not shown are plain and unornamented.

I claim:

The ornamental design for a bathroom unit, as shown and described.
